UNITED STATES PATENT OFFICE.

WILLIAM A. COPELAND, OF BOSTON, MASSACHUSETTS, ASSIGNOR TO INTERNATIONAL SHOE COMPANY, OF ST. LOUIS, MISSOURI, A CORPORATION OF DELAWARE.

SOLE-WAXING MACHINE.

Application filed December 9, 1925. Serial No. 74,378.

This invention relates to mechanism for coating a surface with a liquid, and is especially adapted for applying a coating of hot wax to the bottoms of shoe soles. Heretofore, 5 the application of the wax has been difficult, as the methods so far devised have proved to be incapable of applying a thorough, even coating in a relatively brief time. By my invention, hot wax is picked up from a container 10 and is quickly and evenly applied to the soles, the wax being to some extent worked into the surface of the soles.

Further advantageous features will be found in the device as illustrated in the drawings, in which

Figure 1 is a side elevation of a wax-applying machine embodying my invention.

Figure 2 is a plan of the same.

Figure 3 is a detail section of the wax-lifting wheel taken on the line 3—3 of Figure 2.

Figure 4 is a side view of a portion of an applicator chain.

Figure 5 is a section on the line 5—5 of Figure 4.

Figure 6 shows how the applicators engage the sole of a shoe.

Figure 7 is a view on the line 7—7 of Figure 2.

Figure 8 is a section on the line 8—8 of Figure 2.

Figure 9 is a section on the line 9—9 of Figure 2.

Referring to the drawing in detail, 10 indicates a container for melted wax or any other desired fluid, which may be provided with heating units 11. A suitable wheel 12 is keyed on a shaft 13 to feed the fluid by dipping a portion of its rim into the liquid and lifting a film of liquid from the container as the wheel is rotated. A ratchet 14 is fixed to the shaft 13 and is engaged by a pawl 17 carried by a disk 17^a, which is loosely mounted on the shaft 13 and is oscillated by a link 15, the latter being eccentrically connected to a collar 61 keyed to a shaft 60. The shaft 60 is driven from a shaft 23 by gears 61, 62.

Means are provided for transferring the liquid lifted by the wheel 12 from the wheel and applying it to the article to be coated. 50 These means preferably comprise an applicator such as that indicated at 18, which consists of one or more endless carriers such as chains, three such chains, 19, 20, 21, being shown in the drawing passed around suitable sprockets which are mounted on shafts 22,

23. Each chain preferably comprises a series of work-engaging members 24. These members may be formed, as shown in Figure 5, with relatively narrow body portions 24^a on both sides of which links 24^b may be attached to connect successive members together into a chain. The body portion 24 is preferably surmounted by a broader work-engaging portion 25, the flat surface 25^a thereof being designed to carry the liquid and rub it on the surface to be treated. The portion 25 being preferably broader than the body portion 24^a may be made to overhang the links 24^b, protecting them and preventing their catching on links of the next adjacent chains. A wiper 26 is suitably positioned to engage the faces 25^a as they pass from contact with the wheel 12 and to spread the liquid thereover, at the same time removing any excess of liquid that may have been received thereon. The work-engaging links 24 of the three chains 19, 20, 21, are preferably in staggered relation, as shown in Figure 2. A heating unit 27 may be supported, as by a bracket 28, adjacent to a portion of the chains to heat them as they pass by. The applicator chains are yieldingly tensioned to any desired degree by a spring 29 which is attached to an end of a lever 30 in the opposite end of which is journaled the idle shaft 22 which carries the sprockets, one set of sprockets supporting the applicator chains. The other set of sprockets is carried by the shaft 23, which is driven through mitre gears 31, 32, from a shaft 33. The lever 30 is suitably mounted, as at 34, on a bracket 35 projecting from the machine base 36. This base also carries a suitable standard 37, on which the above described mechanism is supported. The base 36 also carries a support and housing 38 for the transmission mechanism which drives the shaft 33 and the liquid applying mechanism connected therewith. When using the apparatus, the article to be coated, such as a shoe sole, is preferably held against the applicator chains from below, as indicated in Figure 6. The work-engaging surfaces 25 of the chain links having received a quantity of liquid from the wheel 12, which liquid has been spread over the faces evenly by the wiper 26, rub the liquid on and into the surface of the work as it is moved transversely of the chains. The large number of links engaging the work in the process of coating it ensures a thorough application of an even smooth coat.

The power transmission mechanism comprises a suitable chain 39 connecting a sprocket 40 mounted on a shaft 33^a with another sprocket 41 mounted on the shaft 42. 5 The shafts 33 and 33^a are in alignment, their abutting ends being slotted, as indicated in Figure 9, for interlocking engagement. This 10 permits the independent removal of the applicator mechanism and the driving mechanism for convenience in making repairs or adjustments. The shaft 42 also carries revolving brushes or buffer wheels 43, 44, which may be used to finish and polish articles which have been coated. The shaft 42 is driven through 15 a pinion 45 mounted thereon, which has spiral teeth meshing with a spiral gear 46. A suitable ball bearing 52 may be mounted on the shaft 42 to take the lateral thrust of the gear 46 on the pinion 45. The gear 46 is mounted 20 on a shaft 47 which carries a driving pulley 48 and an idle pulley 49, about which a belt extends from any convenient source of power. A belt shifter 50 is slidably mounted on the 25 casing 38 to move the belt from one pulley to the other. A hand plate 51 is provided for operating the belt shifter.

It is to be understood that this invention is not limited by the disclosure in the drawing and the description contained herein, but is 30 subject to any modifications and changes which fall within the spirit and scope of the appended claims.

I claim:

1. In a device of the class described, a 35 liquid container, means for heating the container, means for feeding liquid from the container, means for transferring the liquid from the feeding means and applying it to work held thereagainst, said transferring and applying means comprising a plurality of chains positioned side by side for contact with said feeding means; means adjacent a portion of said chains for heating said chains, and means for maintaining a yielding tension on said chains. 40

2. In a device of the class described, a liquid 45 container, a wheel positioned with a portion of its periphery immersed in the liquid, means for rotating said wheel, and means for transferring liquid from said wheel and applying it to work held thereagainst, said transferring and applying means comprising a series of members having work-engaging faces, links connecting successive members into an endless chain, sprockets for supporting said chain, one of the sprockets being driven, and means for maintaining a yielding tension on said chain. 50

3. The combination with a liquid container

and means for feeding liquid from the container, of means for applying liquid to work held thereagainst comprising a plurality of endless chains positioned side by side, having series of members with work-engaging faces, said series being in staggered relation and said members being adapted to receive liquid from the feeding means and rub it on the surface of the work, and means for spreading the liquid received from the feeding means over the work-engaging faces of said members. 60 65

4. In a device of the class described, a liquid container, means for heating the container, means for feeding liquid from the container, an elongated flexible endless carrier having a comparatively straight stretch and arranged 75 to contact with said feeding means and receive liquid therefrom, a wiper engaging the carrier, and means for heating the carrier positioned adjacent thereto.

5. In a machine for applying melted wax 80 to shoe soles, a wax container, means for heating the container, means for feeding melted wax from the container, means comprising an endless carrier for receiving wax 85 from said feeding means and applying it to a sole held thereagainst, means for maintaining a tension on the carrier, and stationary means for heating the carrier.

6. In a device of the class described, a liquid 90 container, means for heating the container, means for feeding liquid from the container, an endless carrier arranged to contact with said feeding means and receive liquid therefrom, said carrier having a horizontally disposed portion for engaging work applied thereto, and a liquid-spreading device in contact with the carrier at a point between the feeding means and the work-engaging portion of the carrier. 95

7. In a device of the class described, a liquid 100 container, means for heating the container, means for feeding liquid from the container, an endless carrier arranged to receive liquid therefrom, a pair of wheels supporting said carrier with a pair of substantially horizontal stretches thereof between them, said feeding means being arranged to contact said carrier adjacent to an end of the lower of said horizontal stretches, a wiper contacting said lower stretch adjacent to said feeding means, a heating device adjacent to the upper of said stretches, means for maintaining tension on said carrier, and means for driving one of said wheels. 105 110 115

In testimony whereof I have affixed my signature.

WILLIAM A. COPELAND.
